UNITED STATES PATENT OFFICE.

CHARLES W. COOKSON, OF WILMINGTON, CALIFORNIA, ASSIGNOR OF ONE-FOURTH TO GEORGE F. HIRSCH, OF LONG BEACH, CALIFORNIA.

DESIGN FOR A WRENCH MEMBER.

SPECIFICATION forming part of Design No. 31,005, dated June 13, 1899.

Application filed May 21, 1898. Serial No. 681,379. Term of patent 7 years.

To all whom it may concern:

Be it known that I, CHARLES W. COOKSON, a citizen of the United States, residing at Wilmington, in the county of Los Angeles and State of California, have invented a new and useful Design for a Wrench Member, of which the following is a specification.

This invention is a new and useful design for a wrench member, the essential feature 10 being the open frame of the handle and the ribbed construction of the shank.

The invention consists also in certain other features of design and ornamentation, all of which will be fully described hereinafter.

15 In the drawings forming part of this specification, Figure 1 is a side view of a wrench member constructed in accordance with my design. Fig. 2 is an edge view.

Referring to the drawings, A indicates a

body portion which is in the shape of an oval, 20 and projecting from either side of handle are two parallel flanges B. From the body A extends a projection C, rectangular in cross-section, on each face of which is a longitudinal rib D, which terminate in a circular flange 25 or enlarged portion E, and extending from the lower parallel flange B are the curved arms F.

Having thus described my invention, what I claim as new, and desire to secure by Letters 30 Patent, is—

The design for a wrench member, substantially as herein shown and described.

CHARLES W. COOKSON.
